(57) **CLAIM**

The ornamental design for a closing means for packaging, as shown and described.

DESCRIPTION

FIG. 1 is a front perspective view of the present invention as shown during use in a closed position;
FIG. 2 is a front elevation view of FIG. 1;
FIG. 3 is a rear elevation view of FIG. 1;
FIG. 4 is a left side elevation view of FIG. 1;
FIG. 5 is a right side elevation view of FIG. 1;
FIG. 6 is a top plan view of FIG. 1;
FIG. 7 is a bottom plan view of FIG. 1;
FIG. 8 is a front perspective exploded view of the present invention as shown during use in a closed position;
FIG. 9 is a front elevation exploded view of FIG. 8;
FIG. 10 is right side cross-sectional view of FIG. 1;
FIG. 11 is an alternative front perspective view of the present invention as shown in a closed position;
FIG. 12 is a front perspective view of the present invention as shown during use in an open position;
FIG. 13 is a front elevation view of FIG. 12;
FIG. 14 is a rear elevation view of FIG. 12;
FIG. 15 is a left side elevation view of FIG. 12;
FIG. 16 is a right side elevation view of FIG. 12;
FIG. 17 is a top plan view of FIG. 12; and,
FIG. 18 is a bottom plan view of FIG. 12.
